DESIGN FOR A MUFF OR SIMILAR ARTICLE

Harold Block, New York, N. Y.

Application May 1, 1939, Serial No. 84,695

Term of patent 3½ years

To all whom it may concern:

Be it known that I, Harold Block, a citizen of the United States, residing in New York city, in the county of New York and State of New York, have invented a new, original, and ornamental Design for a Muff or Similar Article, of which the following is a specification, reference being had to the accompanying drawing, forming part thereof.

Fig. 1 is a front elevation of a muff showing my design.

Fig. 2 is a top plan view of the muff shown in Fig. 1.

Fig. 3 is a top plan view of the muff shown in Fig. 1, showing the purse member in opened position.

Fig. 4 is a bottom plan view of the muff shown in Fig. 1.

Fig. 5 is a side elevation of the muff shown in Fig. 1.

I claim:

The ornamental design for a muff or similar article, substantially as shown and described.

HAROLD BLOCK.
